UNITED STATES PATENT OFFICE.

FERDINAND LEHR, OF HOBOKEN, NEW JERSEY.

IMPROVED MACHINE FOR BENDING UMBRELLA-RIBS.

Specification forming part of Letters Patent No. 22,659, dated January 18, 1859.

To all whom it may concern:

Be it known that I, FERDINAND LEHR, of Hoboken, in the county of Hudson and State of New Jersey, have invented, made, and applied to use certain new and useful Improvements in Machinery for Bending Umbrella-Ribs and Similar Articles; and I do hereby declare that the following is a full, clear, and exact description of the construction and operation of the same, reference being had to the annexed drawings, making part of this specification, wherein—

Figure 1 is a plan of my machine complete. Fig. 2 is a side elevation. Fig. 3 is an end view. Fig. 4 is a vertical longitudinal section showing the apparatus for bending the ribs; and Fig. 5 is a partial section showing the feeding-pinchers and parts opposite to those in Fig. 4.

Similar marks of reference denote the same parts.

My said invention relates to machinery for bending wire into loops for forming the ribs or spokes of umbrellas, whereby said loops serve like holes in the ribs for the joints and for receiving the stretchers, it being distinctly understood that my invention does not relate to the rib or spoke itself when bent, the same being patented by Henry Kurth, of Brooklyn, New York, April 29, 1858.

The machinery I make use of for accomplishing the above-mentioned purpose of bending or coiling wire into loops for forming umbrella-ribs may be divided as follows: first, a reciprocating jaw or pincher which feeds or draws the wire, after it has been straightened, into the machine, and then opens, and, leaving the wire to be operated on, turns down out of the way and is drawn back, then turned up, and again seizes the wire; second, a shear having a compound motion to come up and cut off the wire, and then move back out of the way; third, clamps holding the wire near the middle and toward one end while the loops or eyes are being formed; fourth, mandrels and turning-stubs that bend or coil up the wire to form a loop or eye near one end and in the middle part of the rib; fifth, a mandrel and turning-stub which takes the end of the wire after it has been bent at the middle to form the loop and turns thereon a loop or eye for the joint, by which the end of the rib is attached. The parts then return to their former position and the rib drops.

The operation of bending the spokes or ribs being performed in the above order by my machine, the description will correspond thereto in its plan, although but one machine is used and that for producing one article.

In the drawings, *a* is a shaft sustained in boxes *b b*, and rotated by competent power through the crank *c* and handle or crank-pin *c'*, or otherwise.

A is the side frame carrying the mandrels, and *B* is the other side frame, carrying the turning-stubs and parts thereof.

First. On the side frame, *A*, is a *V*-slide, *g'*, carrying the sliding block *g*, on which a short stud, *2*, is attached, that carries the pinchers *e e'*, and on this stud *2* the pinchers can turn down against the stop *7*, in the position shown in Fig. 2 by dotted lines, or be turned up against the stud *6*, as seen in Fig. 5. The pinchers *e e'* are attached together by the screw *5*, and formed with horizontal jaws partially to the side, which take the wire, as shown by red lines in Figs. 1 and 5. The side *e* of the pinchers is longer than the side *e'*, and extends downward through a guide-slot, *4*, and has a pin or stud, *3*, projecting therefrom toward the outside of the machine, where it receives one end of the link *f*, the other end of which is provided with a slot, *1*, that receives the crank-pin *c'*. *9* is a spring tending to open the jaws, the same being attached to the part *e* and acting on a pin, *8*, on the part *e'*, said pin *8* also preventing the jaws opening too far. *d* is a guide through which the wire to form the rib or spoke is led after it has been straightened. The operation of these pinchers is as follows: The crank-pin *c'* being revolved in the direction of the arrows, the link *f* draws the slide *g* along from the position in Fig. 2 to that of Fig. 5, the pinchers being out of the way of the other parts by the pull on the stud *3* acting to turn the pinchers down against the stop *7*. So soon as the crank *c* passes its center, the slide *g* has arrived at its extreme forward movement. As the link *f* is lifted, the pinchers *e e'* are turned up vertically above the shaft *2*, as seen in Fig. 5. The spring *9* keeping the jaws open, they pass over the wire as the same projects from the guide *d*, and as soon as the pin *c'* takes against the end of the slot *1* the pressure first closes the jaws, grasping the wire, and then the further movement causes the link *f* to face the slide *g* along to the other end of the machine, drawing the necessary length of wire

through the guide *d*. Other parts, hereinafter described, then come up and hold the wire, at which moment the crank *c* passes its center, the pressure is released, the spring *g* opens the jaws, dropping the wire, the spring *f'*, taking the stud *3*, throws that forward, inclining the pinchers, as in Fig. 2, and then the pin *c'*, taking the end of the slot *1*, draws the slide *g* back as before. The spring *f'* might be dispensed with; but it makes the pinchers throw backward and downward more quickly, instead of there being a pause while the pin *c'* travels the length of the slot *1*. A similar spring (to *f'*) might be used at the other end to throw up the pinchers; but the same is not always required.

Second. *i* is a shear attached by a screw, *11*, to the bed-piece *h'*. *h'* is the other half of the shear, jointed to *i* by the screw *12* and carrying the cutter *i'*. The end of the shear *h'* projects as a lever toward the shaft *a*, where a cam, *h*, acts on the same and gives a compound motion thereto as follows: The part *10* of the cam *h*, acting on the shear-lever *h'*, moves said shear out of the way of the wire and pinchers *e e'*, (see Figs. 1 and 5,) said shear turning horizontally on the screw *11*. When the wire has been drawn through, as aforesaid, the end of *h'* being no longer acted on by cam *10*, the spring *i''*, which serves to open the shears as well as to draw the end of *h'* against the cam, on account of its diagonal position, moves the shears laterally, so that the jaws pass above and below the wire, and the cam *h*, now acting, throws down the cutter *i'* and separates the wire, after which the cam *10*, again operating, moves the shears laterally out of the way.

Third. The wire is laid along by the pinchers *e e'* above the ledges *13 14*, Fig. 5, the turning-stubs and mandrels *p p'* are brought up, as hereinafter shown, which prevent the wire escaping. The clamping-levers *k k'* are then brought down to hold said wire firmly by the following means, while the turning operations, Fig. 4, are performed. The levers *k k'* are on fulcrums in the blocks *k'' k'''*. Their outer ends are connected by links *15 15* to bent levers *16 16*, the ends of which are connected to the sliding bar *l* in guides *l'*. *l''* is a spring acting to slide said bar *l* lengthwise and force up the outer end of the levers *k k'* and cause the inner ones to clamp the wire. *l''* is a cam on the main shaft, which, acting against the end of the bar *l* and being properly shaped and timed, raises the inner ends of the levers *k k'*, while the finished spoke drops out and the wire is laid by the pinchers on the ledges *13* and *14* and beneath the ends of said levers *k k'*, as aforesaid.

Fourth. To coil or bend up the wire at the middle and one end to form the eyes or loops, I cause the motion of the bar *l*, aforesaid, to project and retract the mandrels *z z*, that are fixed to the slides *m m'*, and determine the size of the loop or eye formed in the wire rib. *18* are levers on the fulcrums *19 19*, attached at the upper ends to said slides *m m'* in the

blocks *k''* and *k'''*. The lower ends of these levers *18 18* set in diagonal jaws or slots *20 20* on the bar *l*, so that as the bar *l* is moved by the spring *l''* to clamp the wire by the levers *k k'*, the mandrels *z z* are projected out of the blocks *k'' k'''*, so as to be ready to have the wire bent around the same by the means next described. *n''* is a cam on the shaft *a*, which acts on the slide-bar *n'*, from which links *22 22* connect to cranks *23 23* on the lower ends of vertical shafts *n'' n''*. *24 24* are arms on the upper ends of the shafts *n''*, connected by links *25 25* to the stocks *o o*, that move in **V**-slides *o' o'*, and carry the turning shafts *p p'* and stubs *x x*, and *21* is a spring acting to slide the bar *n'* toward the cam *n''*. The operation of this part is, that the cam *n''*, being properly shaped and timed, moves from and releases the slide *n'* immediately after the pinchers *e e'* have passed along, carrying the wire, as aforesaid, so that the spring *21*, acting through said bar *n'*, cranks *23* and *24*, links *22* and *25*, and the shafts *n''*, projects the stocks *o*, so that the ends of the shafts *p p'* come up and hold said wire, the turning-stubs *x* being above the wire, as seen in Fig. 4, and the ends of the shafts *p p'* being provided with holes into which the mandrels *z z* pass when projected, as before set forth. The shafts *p p'* are revolved while pressed against the wire by means of the gears *r'* and *r''*, there being three gears *r'* and two gears *r''*, so that one movement of the rack *r* will turn said shafts *p p'* in opposite directions, which causes the stubs *x x* to turn or twist the wire, around in the manner represented by the red lines and arrows, Fig. 4, the inner faces of the blocks *k''* and *k'''* being formed as an incline from the ledges *13* and *14*, so that the wire, when turned into an eye, is coiled or laid double at the back of the eye, the spring *21* allowing the shafts *p p'* to move slightly back as the turning progresses. It will be seen that the shaft *p* acts near the end to form the eye to which the edge of the umbrella-cover is attached, and that the shaft *p'* and its stub sweeps the wire around, as shown in Fig. 4, to form the eye near the middle, and causes the moving end of the wire to pass down between the jaws *32*, beneath an offset and over a mandrel on which the wire has an eye bent up at the end thereof, as heretofore described. The rack *r* receives its motion from a crank, *q*, at the end of the shaft *a*, with its pin acting in a slot, *27*, of the connecting-rod *q'*, that is attached at *26* to the said slide *r*, the object of the slot *27* being to allow a pause after the turning operation, before described, for the end to have an eye turned therein, and for the cam *n''* to force along the slide-bar *n'* and slide the stocks *o o* and shafts *p p'* away from the finished rib, when the crank-pin, taking the other end of the slot *27*, slides the rack *r* to its former position, turning back the shafts *p p'*, ready to be again projected and act upon another wire, as before specified.

Fifth. The rack *u*, similar to the rack *r*, also moves in a **V**-recess in the side *B* of the bed,

and acts to rotate the shaft p^2 and its stub x' through the gears u' , and said stub x' bends the end of the wire into an eye, (see red lines, Fig. 4,) in the same manner as before detailed relative to the shafts p p' . The endwise motion is given to the shaft p^2 and stock s' in the slides s' by means of the link 31, arm 30, shaft s , crank 29, and link 28, to the sliding bar n and spring 41, the cam n^2 being so formed and positioned that the stock s' and turning shaft p^2 come up and take the end of the wire as it sweeps around and arrives at the jaws 32, (see Fig. 4,) and simultaneously the mandrel z' is projected by a link, s^3 , from the arm 30 to a lever, 34, taking the slide m^2 in the block k^4 , at the end of which slide m^2 is the said mandrel z' . From the pin of the crank q is a second crank, t , set at such an angle to the former that the pin t' , taking the end of the slot 35 in the connecting-rod t^2 , gives the sliding motion to the rack u , and rotates the shaft p^2 and its stub as soon as the said shaft p^2 is pressed against the wire, as aforesaid, and when the eye has been bent on the end, as before described, the cam n^2 forces the shaft p^2 back, drawing out the mandrel z' , and the spoke or rib falls away completed, and the pin t' , taking the other end of the slot 35, turns the shaft p^2 back to its former position. It will be evident that by the arrangement of the cranks q and t , in connection with the slots 27 and 35 in the connecting-rods q^2 and t^2 , the operations of turning the shafts p' and p^2 are performed successively, so as to act on the wire first to form the middle eye and then the end eye or loop.

Having thus described the construction and operation of the successive parts, I will briefly recapitulate the various operations: The pinchers seize and draw through the wire, the shafts p p' come up, the levers k k' clamp the wire, the pinchers open, turn down, and are drawn back out of the way, the center and end eyes are turned by the stubs x x around the mandrels z z as they are projected, the shaft p^2 comes up, the mandrel z' is projected, and the end eye or loop is turned, the shafts p , p' , and p^2 move back successively, and the mandrels z z z' are withdrawn and the finished rib or spoke drops away complete. The pinchers e e' by this time have been turned up vertically and again seize the wire, the other parts have resumed their former positions, and the motions are performed as before.

I do not claim a mandrel around which the wire is bent by a revolving stub, as such mandrel has been affixed to the shaft carrying the revolving stub. In that case, however, difficulty existed in removing the spoke or rib, when bent, from off the said mandrel; but by my machine, the mandrels and bending-stubs withdrawing from each other and the mandrels pulling out of the holes or eyes, this difficulty is avoided.

What I claim as my invention, and desire to secure by Letters Patent, is—

1. A reciprocating pincher taking the wire from a fixed and drawing the same through the machine, dropping from said wire, and then returning below to its previous position, so as to be out of the way of the bending or coiling of the wire into eyes or loops, as set forth.

2. Attaching said pinchers on a traveling carriage by one side thereof, while the power for sliding said pinchers lengthwise of the machine is applied to the other jaw, whereby the clamping and releasing of the wire are effected by the act of moving said pinchers, as set forth.

3. Attaching one end of said pinchers on a stud or shaft, in combination with the stops 6 and 7, spring 9, and slotted connecting-link f , whereby the sliding, clamping, depressing, and elevating motions are given the pinchers by the reciprocations of said rod f , as set forth.

4. The shear i i' , receiving the compound motion set forth from the cams h and 10 , in the manner and for the purpose specified.

5. The clamping-levers k k' , in combination with the ledges 13 14 and shafts p p' , that press against and hold the wire while the loops are being formed, as set forth.

6. The mandrels, in combination with the turning shafts and stubs, when the said mandrels are projected from the blocks or their equivalents, for the wire to be bent around the same to form the loops or eyes in the spokes or ribs, and withdrawn from said eyes when the same have been bent, substantially as set forth.

7. The arrangement of the sliding bar l and the connections therefrom to the clamping-levers k k' and slides m m' , whereby the clamps and mandrels z are simultaneously actuated, as set forth.

8. The sliding stocks o o , carrying the shafts p and turning stubs for allowing the withdrawal of said stubs out of the way of the traveling pinchers, substantially as set forth, and, in combination therewith, the bar N and connections therefrom to said stocks o o , for communicating endwise motion to said stocks, for the purpose and as specified.

9. The sliding mandrel z' and turning shaft p^2 , connected as set forth, in combination with the jaws 32, or their equivalents, for turning the eye or loop in the end of the spoke or rib, as described and shown.

10. The arrangement of the cranks q and t and slotted connecting-rods q^2 t^2 , for communicating motion successively to the slides r and u' and from the same to the turning-stubs or loop-formers, as set forth.

In witness whereof I have hereunto set my signature this 17th day of December, 1858.

F. LEHR.
